Patented Aug. 17, 1915.

UNITED STATES PATENT OFFICE.

ANDREW A. HOWARD, OF SANTA MARIA, CALIFORNIA, AND JERRYMIAH M. BURGER,
OF ARDMORE, OKLAHOMA.

RATCHET-SWIVEL FOR DRILLING-CABLES.

1,150,196.

Specification of Letters Patent. Patented Aug. 17, 1915.

Application filed October 27, 1913. Serial No. 797,607.

To all whom it may concern:

Be it known that we, ANDREW A. HOWARD and JERRYMIAH M. BURGER, citizens of the United States, residing at Santa Maria and 5 Ardmore, respectively, in the counties of Santa Barbara and Carter, respectively, and States of California and Oklahoma, respectively, have invented certain new and useful Improvements in Ratchet-Swivels for Drilling-Cables, of which the following is a specification.

This invention relates to new and useful improvements in ratchet swivels such as are employed in connecting wire rope leads with 15 drilling tools in the boring or drilling of Artesian or oil wells, and aims particularly to provide a device of this character which is extremely simple in construction, may be cheaply manufactured, will be durable and 20 efficient in its action, and is composed of a minimum number of parts so arranged that the wear on the ratchet parts is inappreciable.

In drilling wells with the common drill, 25 it is customary to employ a solid rope socket to lessen the expense of operation. However, when undermining, a ratchet rope socket is indispensable. It is, therefore, often necessary to change from one type of 30 rope socket to the other. This change involves considerable loss of time and, consequently, considerable expense, since the babbitt with which the wire rope is held in the solid socket must be melted out, the 35 wires then bent and fitted into the ratchet socket, and the babbitt reheated so that the rope will be fixed in the proper position. The time usually necessary to make such a 40 change is from one to one and one-half hours.

Being cognizant of the above conditions, the present invention aims to obviate the difficulties now encountered in substituting a solid socket for a ratchet socket, and vice-versa, by providing a novel form of ratchet 45 swivel which is independent of the rope socket and may be quickly interposed between the rope socket and the sub, with a minimum expenditure of time and labor.

50 The above and additional objects are accomplished by such means as are illustrated in the accompanying drawings, described in the following specifications, and then more particularly pointed out in the claims which 55 are appended hereto and form a part of this application.

With reference to the drawings, wherein there has been illustrated the preferred embodiment of this invention as it is reduced to practice, and throughout the several 60 views of which similar reference numerals designate corresponding parts, Figure 1 is a longitudinal section taken through the ratchet swivel, illustrating the various elements of the device in operative assembled 65 relation; Fig. 2 is an enlarged view illustrating in section the preferred form of ratchet mechanism; Fig. 3 is a detail perspective of the ratchet pawl in disassembled 70 relation; Fig. 4 is a detail view in top plan of the ratchet ring; and Fig. 5 is a side elevation of the ratchet cage.

Proceeding now to the description of the drawings: The preferred embodiment of this invention includes a cage or housing 75 10 in which the ratchet mechanism is arranged, and through which a swivel connecting rod 11 extends so that it may be operatively connected at one terminal to the ratchet device, and at its other terminal 80 to the rope socket. The housing 10 is annular in shape, and is internally screw-threaded at its lower terminal as at 12 to receive the reduced threaded neck 13 of the sub, to which latter member a string of 85 tools is attached in the usual manner during the drilling of the well. The central channel or opening of the housing 10 is reduced at its upper terminal to snugly receive the reduced portion 14 of the connecting rod 11, 90 as will be readily observed upon reference to Fig. 1. This reduced opening is flared at the upper terminal of the member 10 to receive the enlarged portion 15 of the connecting rod. Upon reference to Fig. 1, it will 95 be noted that the connecting rod 11 is enlarged at its upper end, as at 16, and that an annular shoulder 17 is formed at the juncture of the enlarged portion 16 and the portion 15. This shoulder bears on the 100 upper edge of the housing 10 and co-acts with the tapered portion 15 in relieving the rod and casing of undue strain. The upper terminal of the connecting rod 11 is reduced and externally screw-threaded, producing 105 an attaching nipple 19, which is adapted to receive a rope socket, such as is ordinarily provided for wire rope. The lower terminal of the connecting rod 11 is screw-threaded and extends to a point approximately 110 midway the length of the main chamber of the housing 10.

As a means for normally holding the connecting rod against withdrawal from the housing 10, and at the same time permitting it to be readily removed, should necessity demand, there has been provided a locking nut 20 which is threaded on the lower terminal of the rod 11 which projects into the main chamber of the housing 10. Between the upper face of the locking nut 20 and the annular shoulder 21, which is defined at the juncture of the reduced passage of the member 10 and the main chamber thereof, is interposed a pair of bearing rings 22 and 23, the adjacent faces of which are formed with annular ball bearing race-ways adapted to receive ball bearings 24. It will be readily observed that by interposing these ball bearings between the locking nut and the shoulder 21, the rod 11 is permitted to rotate freely within the casing 10.

The actual construction and arrangement of the several parts of the housing and the connecting rod being thus disclosed, it now remains to describe the ratchet mechanism which operates to check the positive rotation of the rod 11 within the housing 10, at the same time permitting the rod to rotate negatively. In this connection, it may be well to observe that the ratchet mechanism is provided for the customary purpose of allowing the rope to resume its natural form after it has been elongated by reason of the weight of the drilling tools during their movement through the well and the consequent torsional action on the strands of the rope.

The preferred form of ratchet mechanism employed includes a cage 25, a ratchet pawl 26, and a ratchet ring 27. The cage member 25 is annular in shape, and is formed in the nature of a cored casting, the upper portion of which is cored out and internally screw-threaded to receive the lower threaded terminal of the rod 11, as indicated at 28. A reduced passage 29 is formed in the lower portion of the member 25 and communicates with the enlarged passage 28. An annular depending flange 30 is formed on the lower end of the member 25, being designed to serve as a hub for the member 25 when this latter member is in assembled relation to the ratchet ring to be hereinafter described. Diametrically arranged slots are formed in the flange 30 and the lower portion of the member 25, as indicated at 31. These slots receive the arms of the ratchet pawl. This ratchet pawl, as best illustrated in detail in Fig. 3, consists of a bar 32, the terminals of which are oppositely beveled at their lower edges, as at 33. This bar is pivoted at a central point on a pivot pin 34 carried by a pawl hub 35. This hub 35 is annular in shape, and is bifurcated to receive the pawl bar 32. On the upper portion of this pawl hub 35 is formed a re-

duced boss 36. Upon reference to Fig. 2, it will be observed that in the assembled relation of the parts, the boss 36 extends through the reduced bore or passage of the member 25 which, being of greater diameter than the boss, provides an annular chamber 37 between the boss and the wall of the bore. In this annular chamber is received the lower terminal of a helical spring 38. This spring is of the expansion type and, bearing at its upper terminal against the lower terminal of the rod 11, operates to normally hold the terminals of the pawl in engagement with the ratchet ring 27. This ratchet ring is also annular in shape, and is provided on its upper edge with ratchet teeth 39. A screw-threaded neck or boss 40 extends downwardly from the under face of the ratchet ring, being adapted for screw-threaded engagement with the threaded bore 85 formed in the reduced neck of the tool sub 13.

From the foregoing, the operation of the device will be apparent: The rope socket is threaded on the member 19 of the rod 11, and the string of well tools is connected to the sub 13 in the usual manner. The tools are then lowered into the well. It is apparent that the weight of the tools on the wire rope or cable will cause the strands of the cable to untwist or turn in the direction tending to elongate the cable. This twisting obviously produces the engagement of the pawl 32 with the teeth of the ratchet ring 27, resultantly producing the rotation of the sub 13 and housing 10 with the rod 11. When the drilling tools strike the rock or other working surface, the cable is relieved of the weight of the tools, and immediately retwists until its strands are in normal position. It is thus possible to obtain the necessary revolution of the tools at each impact of these members with the surface to be drilled, insuring the drilling of a straight round hole, without requiring the operator to manually revolve the tools from the top of the well.

In reduction to practice, it has been found that the form of this invention illustrated in the drawings, and referred to in the above description as the preferred embodiment, is the most efficient and practical; yet realizing that the conditions concurrent with the adoption of this device will necessarily vary, it is desired to emphasize the fact that various minor changes in details of construction, proportion and arrangement of parts may be resorted to, when required, without sacrificing any of the advantages of this invention, as defined in the appended claims.

What is claimed is:—

1. A device of the character described including a housing, a swivel rod extending into the housing and having its lower ter- 130

5 minal screw-threaded, means for holding the rod against withdrawal from the housing, a sub adapted to be threaded into the lower end of the housing, and a ratchet mechanism connecting the lower terminal of the swivel rod with the sub, said ratchet mechanism including a ratchet ring detachably connected to the sub, a pawl cage detachably connected to the lower terminal of 10 the swivel rod, and a spring-pressed pawl mounted for sliding movement in the cage and engageable with the ratchet ring.

2. A device of the character described including a housing, a swivel rod extending 15 through the housing at one end thereof, a sub extending through the housing at the other end thereof, and a ratchet mechanism interposed between the sub and rod for operatively connecting the sub and rod, said 20 ratchet mechanism including a ratchet ring, a pawl cage, a pawl hub mounted for sliding movement in the cage, a pawl bar pivoted in the hub and a spring arranged in the cage and bearing against the pawl hub 25 for normally holding the pawl in engagement with the ratchet ring.

3. A device of the character described including a housing, a swivel rod, a sub, and a ratchet mechanism arranged in the housing and operatively connecting the adjacent terminals of the sub and rod, said ratchet mechanism including a ratchet ring having threaded engagement with the sub, a pawl cage having threaded engagement with the 30 swivel rod, a pawl hub mounted for vertical sliding movement in the cage, a pawl bar pivoted at its central point within the cage and a spring arranged in the cage and bearing at one terminal against the pawl hub 35 and at its other terminal against the rod for normally holding the pawl in engagement with the ratchet ring.

4. A device of the character described including a housing, a swivel rod, a sub, a ratchet mechanism interposed between the adjacent terminals of the sub and the rod for operatively connecting the same, said mechanism including a ratchet ring having threaded engagement with the sub, a ratchet 45 cage having threaded engagement with the rod, there being an opening formed in the bottom wall of the cage, a pawl, said pawl including a bifurcated hub, a bar member pivoted in the bifurcation of the hub, a boss 50 of less diameter than the hub extending upwardly from the upper end thereof, said hub being received within the opening of the bottom wall of the cage and being of a diameter less than the diameter of said 55 opening, and a spring bearing at its upper terminal against the rod and having its lower terminal wound around the said boss and bearing against the said hub for nor- 60

mally holding the bar member in engagement with the ratchet ring.

5. A device of the character described including a housing, a swivel rod, a sub, and a ratchet mechanism interposed between the adjacent terminals of the sub and rod and arranged in the casing for operatively connecting the rod and sub, said ratchet mechanism including a ratchet ring having threaded engagement with the sub, a pawl cage having threaded engagement with the terminal of the said rod, an annular depending flange formed on the cage, there being diametrically opposed vertically extending slots formed in the flange and lower portion of the cage, a pawl member including a hub, a reduced boss formed on the upper terminal thereof, and a pivoted bar member, said bar member having its terminal portions arranged in the said slots, and yieldable means surrounding the boss and engaging the hub for normally holding the bar member in engagement with the ratchet ring.

6. A device of the character described including a housing, a swivel rod, a sub, and a ratchet mechanism interposed between the adjacent terminals of the sub and rod for operatively connecting the same, said mechanism including a ratchet ring, a pawl cage, a pawl hub having its upper terminal freely received within the cage and its lower terminal freely received within the ratchet ring, 95 a pawl bar pivoted within the hub, and yieldable means for normally holding the pawl bar in engagement with the ratchet rings.

7. A device of the character described including a housing, a swivel rod, a sub, and a ratchet mechanism operatively connecting the sub and rod, said mechanism including a pawl cage having the lower terminals of its wall bifurcated at diametrically opposite points, a pawl hub slidably received within the cage, a pawl bar extending transversely through the hub and pivoted therein, the terminals of said pawl bar being mounted within the bifurcations, a ratchet ring receiving the lower terminal of the pawl bar 110 and the lower terminal of the hub and engageable by the hub, and yieldable means normally holding the pawl bar in engagement with the ratchet ring.

In testimony whereof we affix our signatures in presence of two witnesses.
